UNITED STATES PATENT OFFICE.

GEORGE P. PAULMAN AND PETER J. SENSABAUGH, OF ELMIRA, NEW YORK.

DESIGN FOR A SIFTER.

SPECIFICATION forming part of Design No. 24,741, dated October 8, 1895.

Application filed February 26, 1895. Serial No. 539,674. Term of patent 7 years.

To all whom it may concern:

Be it known that we, GEORGE P. PAULMAN and PETER J. SENSABAUGH, residing at Elmira, in the county of Chemung and State of New York, have invented a new and original Design for Sifters, of which the following is a full, clear, and exact description, reference being had to the accompanying drawings.

Figure 1 shows a perspective view of the sifter illustrating our design, and Fig. 2 is a side elevation of the body portion.

The body of the sifter comprises two quadrilateral-shaped sides A A', the top edge a^1 of said sides being longer than the bottom edge a^2 . The front edge a^3 is vertical and perpendicular to the top and bottom edges. The edge a^4 is oblique, being inclined, as shown.

The bottom of the sifter and the rear wall are rectangular in their general contour. The front wall C' is rectangular and only partially covers the front of the sifter. The sides A A' are extended toward the front by the addition of an extension E, which is given the shape of a truncated isosceles triangle, the said triangle being tilted so that one of its sides is coincident with and formed by an imaginary extension of the vertical front edge

a^3 of the sides. The base c of the extension E is therefore inclined upwardly with respect to the lower edge a^4 of the sides, forming an 30° obtuse angle thereby. The truncated triangular extensions begin where the lower edge of the front wall C' terminates. The truncated portion e' of the triangle forms an acute angle with the vertical edge a^3 of the sides 35° . The upper truncated edge e' of the triangular extensions E E' are united by an oblong-shaped plate e^2 . The plate e' , the extensions E E', and the bottom B form a rectangular opening E², as shown. The sides A 40° A', and the front and rear walls C C' form a rectangular main body portion of the sifter.

What we claim as new, and desire to secure by Letters Patent, is—

The design for a sifter substantially as shown and described.

In testimony whereof we affix our signatures in the presence of two witnesses.
